Inventor:

Heinrich EckschLAGER

by Reinhardt
Attorney.

UNITED STATES PATENT OFFICE.

HEINRICH ECKSCHLAGER, OF BERLIN-FRIEDENAU, GERMANY.

LIGHT PROJECTOR.

Application filed July 7, 1924, Serial No. 724,603, and in Germany August 11, 1923.

My invention relates to light projectors, search lights and the like and more particularly to the reflectors for use with such apparatus.

- 5 It is an object of my invention to provide a reflector which projects to either side and partly to the rear the light rays emitted from the source of light cooperating with it. If a reflector of this type is combined 10 with a normal dish- or cup-shaped reflector reflecting a cone of light, the normal reflector being arranged within and surrounded by the new reflector, there results a combination which allows obtaining a lighted 15 area which exceeds a hemisphere and is about equal to three quarters of a sphere, the novel reflector emitting a beam of light of annular section which merges in the cone of light formed by the normal reflector and is 20 projected to the sides and to the rear. A reflector according to this invention preferably comprises an annular convex reflecting surface which is so arranged in relation to an annular concave reflecting surface that 25 the light rays projected onto said concave surface by said convex surface are partly reflected to the rear.

In the drawings affixed to this specification and forming part thereof a device embodying my invention and comprising an annular reflector of channel like cross section is illustrated diagrammatically by way of example.

In the drawings

- 35 Fig. 1 is a front elevation, and Fig. 2 a cross section on the line II-II in Fig. 1.

The drawings show an annular reflector surrounding a cup-shaped reflector of the 40 normal type, but it is to be understood that the former may also be used by itself or in combination with any other type of reflector.

The cup-shaped reflector *a* has four lamps 45 *b* mounted therein in the usual manner. It is surrounded by the annular reflector *c* of channel like cross section, the adjoining edges of the reflectors being connected by soldering or by other suitable means. The

50 annular reflector *c* is substantially concave but provided with a convex reflecting surface *d* at the rear. Four lamps *e* are arranged in this reflector. The two combined reflectors are mounted on a base plate *f*.

55 The current conducting wires are not shown

for the sake of simplicity and may be arranged as desired. The base plate *f* is secured on a shaft *g* which may be driven by an electromotor, not shown. On the shaft *g* two slip rings *h*, *i* are provided to which current is supplied by brushes *k*, *l*.

60 The reflector *a* reflects the normal cone of light to the front. In the annular reflector *c* the light rays emitted by the lamps *e* are partly projected to the front and partly onto the surfaces *c* and *d* of the reflector. The rays which strike the concave surface *c* of the reflector are partly projected onto the convex surface *d* which projects part of them back onto the concave surface *c* which 70 thus projects to the sides and partly to the rear a beam of light of annular section as indicated by the dotted lines *o* in Fig. 2. The annular beam combines with the cone of light emitted by the normal reflector *a* 75 so that an area of light radiation is formed as indicated by the lines *m* and *o* in Fig. 2. As clearly shown in Fig. 2 this area exceeds a hemisphere and is practically equal to three quarters of a sphere.

80 The intensity of radiation can be increased by causing rotation of the shaft *g* which carries the device.

The new reflector is also an important improvement if used in connection with 85 motor cars, a single reflector sufficing to light not only that part of the road which is in front of the driver, but also the sides.

I wish it to be understood that I do not desire to be limited to the exact details of 90 construction shown and described, for obvious modifications will occur to a person skilled in the art.

I claim:—

1. A reflector comprising an annular 95 concave reflecting surface and an annular convex reflecting surface said concave surface being adapted to reflect to the rear of said reflector light rays projected onto it by said convex surface and a cup-shaped reflector surrounded by and arranged for reflection substantially in the same direction as said channel-shaped reflector.

2. Reflector comprising an annular concave reflecting surface in front of and an 100 annular convex reflecting surface at the rear of the source of light, said concave surface being adapted to reflect to the rear of said reflector light rays projected onto it by said convex surface and a cup-shaped re- 110

- reflector surrounded by and arranged for reflection substantially in the same direction as said channel-shaped reflector. -
3. Reflector comprising an annular concave reflecting surface in front of and an annular convex reflecting surface at the rear of the source of light, said convex surface extending beyond said concave surface, said concave surface being adapted to reflect to the rear of said reflector light rays projected onto it by said convex surface and a cup-shaped reflector surrounded by and arranged for reflection substantially in the same direction as said channel-shaped reflector. 15
4. An annular reflector of U-shaped cross section comprising a concave and a convex reflecting surface, said concave surface being adapted to reflect to the rear of said reflector light rays projected onto it by said convex surface and a cup-shaped reflector surrounded by and arranged for reflection substantially in the same direction as said channel-shaped reflector. 20

In testimony whereof I affix my signature.
HEINRICH ECKSCHLAGER.
